CLAIM

The ornamental design for a compression girdle, as shown and described.

DESCRIPTION

FIG. 1 is a perspective view of a compression girdle, in an open position, showing my new design;

FIG. 2 is a front elevational view of the compression girdle shown in FIG. 1 in position on a torso shown in broken lines;

FIG. 3 is a rear elevational view of the compression girdle shown in FIG. 2;

FIG. 4 is a right side elevational view of the compression girdle shown in FIG. 2, the left side elevational view being a mirror image thereof;

FIG. 5 is a top plan view of the compression girdle shown in FIG. 2; and,

FIG. 6 is a bottom plan view of the compression girdle shown in FIG. 2.

The broken line showing of the torso is for illustrative purposes only and forms no part of the claimed design. The broken lines shown on the compression girdle are understood to represent stitching.
